PUTTY GUN

Augustine Power, New York, N. Y.

Application April 20, 1948, Serial No. 22,222

9 Claims. (Cl. 222—260)

1

This invention relates to putty guns.

It is particularly directed to a machine for filling openings with putty and buffing the putty, so as to completely fill the openings.

An object of the present invention is to provide a putty gun of the character described, including a plunger, and means to impart a rotary movement to the plunger for buffing putty extruded from the gun in order to completely fill openings left by countersunk flat head nails or screws.

Another object of this invention is to provide a putty gun which may be operated with considerable speed and which leaves a smooth buffed surface when filling openings with putty by means of the gun.

Yet another object of this invention is to provide a putty gun comprising a plunger formed with a helical outer thread, and means to push the plunger so as to cause rotation of the plunger as it is advanced.

Yet a further object of this invention is to provide a putty gun of the character described, comprising a cylinder to receive the putty, a piston at one end of the cylinder, a tube within the cylinder, a plunger within the tube, said tube having slots at one end, and means to press the piston for forcing putty through the slots in the tube, and a plunger mounted for rotation, as well as longitudinal movement in the tube for pressing the extruded putty out of the gun and for buffing such putty into an opening to be filled.

Still a further object of this invention is to provide a strong, durable gun of the character described, provided with a trigger action to advance the plunger, and which shall yet be inexpensive to manufacture, easy to operate, easy to refill and assemble, and which shall yet be practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown various illustrative embodiments of this invention,

Fig. 1 is a side elevational view of a putty gun embodying the invention;

Fig. 2 is a front elevational view of a putty gun;

Fig. 3 is a rear elevational view thereof;

Fig. 4 is an expanded elevational view of the putty gun with parts in cross-section;

Fig. 5 is a cross-sectional view taken on line 5—5 of Fig. 4, and

Fig. 6 is a cross-sectional view taken on line 6—6 of Fig. 4.

Referring now in detail to the drawing, 10 60

2

designates a putty gun embodying the invention. The same comprises a cylindrical container 11. Said container 11 has a cylindrical surface 12 closed at one end by an end wall 13. The end wall 13 is formed with a central opening 14. Extending forwardly from the end wall 13 is an axial tube 15. The front edge 16 of the tube 15 is flush with the front edge 17 of the cylindrical wall 12. The front end of the tube 15 is formed with a plurality of spaced longitudinal slots 18 for the purpose hereinafter appearing.

The end wall 13 is formed with a plurality of openings 19 preferably equiangularly spaced. For the purpose of illustration three such openings are shown in the drawing. Extending inwardly from the tube 15 is a radial pin 20. Fixed to the cylindrical wall 12, adjacent the front edge 17 are a plurality of radial pins 22, three such pins being shown for the purpose of illustration. Attached to the bottom of the cylindrical wall 12, and spaced from the front edge 17 thereof is an apertured ear 25. Attached to the rear wall 13, and disposed below the opening 14 is a horizontally disposed pivot pin 26 supported on apertured ears fixed to said rear wall in any suitable manner. Fitted on the front end of the cylindrical wall 12 is a cap 30. The cap 30 has an annular cylindrical wall 31, which telescopes over the front end of wall 12.

The cap 30 also includes a curved or convex front wall 32 formed with a central through opening 33. Extending rearwardly from the front wall 32 at the opening 33 are a plurality of ribs 34 interconnected at their outer ends by an annular ring 35. The ribs 34 are each formed with internal shoulders 36. The cylindrical wall 31 is formed with bayonet notches 37. The cap 30 is fitted into the front end of the cylindrical member 11 and the radial pins 22 engage within the bayonet notches 37. The cap is first pushed in and then rotated for firmly attaching the cap to the cylindrical member. At the same time, the front end 16 of tube 15 is received within the ring 35 and contacts the shoulders 36.

Slidably and rotatably mounted within the tube 15 is a plunger 40. The plunger 40 is formed at its rear end with a plurality of helical grooves 41 into which the inwardly extending pins 20 on the tube 15 project. The front end of the plunger 40 is preferably concave, as at 42.

It will now be understood that when the plunger 40 is pushed forwardly it will rotate.

Means is provided for advancing the plunger with the tube 15. To this end, there is rotatably mounted on the pin 26 a trigger 44. The trigger 44 has a finger engaging portion 45 projecting downwardly below the cylinder 11. It is also formed with an upwardly extending finger 46 bifurcated or formed with a slot 47. Attached to the rear end of the plunger 40 is a headed

screw 48. The shank of the screw passes through the slot 47. The upper end of the finger 46 contacts the plunger. The head of the screw keeps the slotted portion of the finger 46 close to the rear of the plunger. The trigger 44 is also formed with a downwardly and forwardly inclined arm 49. Interconnecting the apertured ear 25 with the aperture in the arm 49 is a coil tension spring 58 which normally tends to rotate the trigger 44 in a clockwise direction about the pivot 26 for retracting the plunger 40. When the plunger is retracted, its rear end projects rearwardly beyond the back wall 13, as shown in Fig. 4 of the drawing. When a finger engages the finger engaging portion 45 and the trigger is pulled back or rotated in a counterclockwise direction, looking at Fig. 4, arm 46 will press the plunger forwardly, and the plunger will at the same time be rotated due to engagement of the pins 20 in the helical grooves 41. When the plunger is fully pressed forwardly, its forward end will protrude forward of the cap, carrying a portion of putty and continue its rotary movement until putty in the hole is buffed. The cylinder 11 or the chamber 51, therein between the tube 15 and the cylindrical wall 12 is filled with putty before the cap is applied.

Means is provided to press the putty through the slots 18 and through the slots 52 formed between the ribs 34 so that as the plunger is advanced and rotated, extruded putty will be pressed forwardly to fill the opening against which the cap is placed and the putty thus pressed outwardly will be buffed due to the rotation of the plunger 40. To this end, there is disposed within the chamber 51 an annular disc or piston 53 formed with a central opening 53a for receiving the tube 15. Attached to the piston 53 are a plurality of parallel rods 54 passing through the openings 19.

Slidably mounted on the cylindrical member 11 is a carriage 55. The carriage 55 comprises an annular ring 56 which telescopes on the cylindrical wall 12. Extending from the ring or sleeve 56 are longitudinal part cylindrical members 57. the rear ends of members 57 are interconnected by an annular ring or sleeve 58 similar to ring 56. Ring 58 is closed by a rear end disc or wall 59, to which the rear ends of the rods 54 are attached. Also fixed to the rear wall 59 is a handle 60. The handle 60 has side walls 61 interconnected by a bottom wall 62 and a rear wall 63. Thus, the handle 60 is hollow and is fixed to both the rear wall 59 and to the sleeve 58. The sleeve 58 is enlarged at its lower end as shown at 64. As the carriage 55 is pressed forwardly, the rods 54 will press the disc 53 forwardly for causing putty to be extruded through the slots 18 and 52.

The putty gun is first loaded with putty, with the carriage in a retracted position. The handle 60 is held in the hand and the gun is pressed against a wall with the opening 23 surrounding the opening or hole in the wall to be filled with putty. The carriage is pressed forwardly and then the trigger 44 is pulled back. Putty will thus be extruded through the slots 18 and 52 and the extruded putty will be pressed into the opening to be filled and the combined rotary and forward movement of the plunger will buff the surface smoothly.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A putty gun comprising a chamber having a rear wall, and an annular wall extending forwardly therefrom, a tube extending forwardly from said rear wall and adapted to contain a cap fitted into the front end of said annular wall, said cap being formed with a central opening, means on said cap to engage the front end of said tube, a plunger in said tube to extrude putty through said central opening, a slot at the front end of said tube establishing connection between said chamber and said tube, an annular piston within said chamber surrounding said tube, a carriage slidably mounted on said chamber, rods interconnecting the piston with said carriage and passing through openings in the rear wall, and a trigger pivotally mounted on said rear wall and engaging said plunger for moving said plunger in said tube.

2. A putty gun comprising a casing having an outer cylindrical wall and end walls formed with central openings, an axial tube interconnecting said openings, said tube being formed with one or more openings adjacent one end thereof, a plunger slidably extending into the tube through its opposite end, said casing being formed with a putty chamber between the tube and said outer cylindrical wall, an annular piston within said chamber and surrounding said tube, means for advancing the plunger toward the first mentioned end of said tube, and means for advancing the piston toward said end of said tube, said plunger being formed with a helical groove, and means on said tube engaging within said groove, whereby said plunger will rotate as it is being advanced toward the first mentioned end of said tube, the means for advancing the plunger within said tube comprising a trigger pivoted to said casing, and means on said trigger engaging said plunger.

3. A putty gun comprising a casing having an outer cylindrical wall and end walls formed with central openings, an axial tube interconnecting said openings, said tube being formed with one or more openings adjacent one end thereof, a plunger slidably extending into the tube through its opposite end, said casing being formed with a putty chamber between the tube and said outer cylindrical wall, an annular piston within said chamber and surrounding said tube, means for advancing the plunger toward the first mentioned end of said tube, and means for advancing the piston toward said end of said tube, said plunger being formed with a helical groove, and means on said tube engaging within said groove, whereby said plunger will rotate as it is being advanced toward the first mentioned end of said tube, the means for advancing the plunger within said tube comprising a trigger pivoted to said casing, and means on said trigger engaging said plunger, and spring means for pivotally moving said trigger.

4. A putty gun comprising a casing having an outer cylindrical wall and end walls formed with central openings, an axial tube interconnecting said openings, said tube being formed with one or more openings adjacent one end thereof, a

plunger slidably extending into the tube through its opposite end, said casing being formed with a putty chamber between the tube and said outer cylindrical wall, an annular piston within said chamber and surrounding said tube, means for advancing the plunger toward the first mentioned end of said tube, and means for advancing the piston toward said end of said tube, said plunger being formed with a helical groove, and means on said tube engaging within said groove, whereby said plunger will rotate as it is being advanced toward the first mentioned end of said tube, the means for advancing the piston comprising a sleeve slidably mounted on said casing, one or more piston rods passing through an end wall of the casing and interconnecting said piston with an end of said sleeve, and a handle on said end of said sleeve.

5. A putty gun comprising a casing having an annular outer longitudinal wall, a central tube passing through said casing, and open at both ends, and end walls interconnecting the tube with said annular wall forming a chamber for putty, a plunger slidably mounted within said tube, said tube being formed with an opening at one end, so that said chamber will communicate with the interior of said tube, a trigger pivoted to one end wall of said casing, said trigger being formed with a slotted arm, an axial pin on said plunger passing through the slotted arm, and means on said tube and plunger, whereby to rotate the plunger upon advancing said plunger within said tube, a piston within said chamber and surrounding the tube, and means to move said piston within said chamber.

6. A putty gun comprising a casing member having a cylindrical wall and an end wall, an axial tube open at both ends and fixed at one end to said end wall, a cap at the opposite end of said cylindrical wall, said cap being formed with a central opening communicating with the tube and having means to engage the free end of said tube, said tube being formed with a slot adjacent the capped end of said cylindrical wall, said casing being formed with a chamber between said tube and outer cylindrical wall, and an annular ring-like piston within said chamber, and adjacent one end of said casing, means to move the plunger longitudinally and rotatably within said tube, means for moving the piston within said chamber, said last mentioned means comprising a sleeve slidably mounted on said casing, said sleeve having an end wall, and one or more rods interconnecting said piston with said end wall and passing through openings in an end wall of said casing.

7. A putty gun comprising a casing member having a cylindrical wall and an end wall, an axial tube open at both ends and fixed at one end to said end wall, a cap at the opposite end of said cylindrical wall, said cap being formed with a central opening communicating with the tube and having means to engage the free end of said tube, said tube being formed with a slot adjacent the capped end of said cylindrical wall, said casing being formed with a chamber between said tube and outer cylindrical wall, and an annular ring-like piston within said chamber, and adjacent one end of said casing, means to move the plunger longitudinally and rotatably within said tube, means for moving the piston within said chamber, said last mentioned means

comprising a sleeve slidably mounted on said casing, said sleeve having an end wall, and one or more rods interconnecting said piston with said end wall and passing through openings in an end wall of said casing, and a handle on said end wall of said sleeve.

8. A putty gun comprising a casing member having a cylindrical wall and an end wall, an axial tube open at both ends and fixed at one end to said end wall, a cap at the opposite end of said cylindrical wall, said cap being formed with a central opening communicating with the tube and having means to engage the free end of said tube, said tube being formed with a slot adjacent the capped end of said cylindrical wall, said casing being formed with a chamber between said tube and outer cylindrical wall, and an annular ring-like piston within said chamber, and adjacent one end of said casing, means to move the plunger longitudinally and rotatably within said tube, means for moving the piston within said chamber, said last mentioned means comprising a sleeve slidably mounted on said casing, said sleeve having an end wall, and one or more rods interconnecting said piston with said end wall and passing through openings in an end wall of said casing, and a handle on said end wall of said sleeve, the means for moving the plunger within the tube comprising a trigger pivoted to the casing and having means to engage said plunger.

9. A putty gun comprising a casing member having a cylindrical wall and an end wall, an axial tube open at both ends and fixed at one end to said end wall, a cap at the opposite end of said cylindrical wall, said cap being formed with a central opening communicating with the tube and having means to engage the free end of said tube, said tube being formed with a slot adjacent the capped end of said cylindrical wall, said casing being formed with a chamber between said tube and outer cylindrical wall, and an annular ring-like piston within said chamber, and adjacent one end of said casing, means to move the plunger longitudinally and rotatably within said tube, means for moving the piston within said chamber, said last mentioned means comprising a sleeve slidably mounted on said casing, said sleeve having an end wall, and one or more rods interconnecting said piston with said end wall and passing through openings in an end wall of said casing, and a handle on said end wall of said sleeve, the means for moving the plunger within the tube comprising a trigger pivoted to the casing and having means to engage said plunger, and spring means to pivotally move said trigger.
